FIG. 3.

INVENTOR:-
ELLEN M. O'NEIL.
BY Martin P. Gruitt, Atty.

UNITED STATES PATENT OFFICE

132,597

DESIGN FOR A DOLL OR SIMILAR ARTICLE

Ellen M. O'Neil, Los Angeles, Calif.

Application October 14, 1941, Serial No. 103,758

Term of patent 7 years

To all whom it may concern:

Be it known that I, Ellen M. O'Neil, a citizen of the United States of America, residing at Los Angeles, in the county of Los Angeles and State of California, have invented a new, original, and ornamental Design for Dolls or Similar Articles, of which the following is a specification, reference being had to the accompanying drawing, forming part thereof.

Fig. 1 is a front elevational view of a doll, showing my new design.

Fig. 2 is a rear elevational view of the doll.

Fig. 3 is a side elevational view of the doll.

I claim:

The ornamental design for a doll or similar article, as shown.

ELLEN M. O'NEIL.
